UNITED STATES PATENT OFFICE.

ARTHUR BRACKLEY, OF JERSEY CITY, NEW JERSEY.

DISPLAY-STAND.

1,072,693.

Specification of Letters Patent.

Patented Sept. 9, 1913.

Application filed December 27, 1912. Serial No. 738,926.

To all whom it may concern:

Be it known that I, ARTHUR BRACKLEY, a citizen of the United States, and residing at Jersey City, in the county of Hudson and 5 State of New Jersey, have invented certain new and useful Improvements in Display-Stands, of which the following is a specification, such as will enable those skilled in the art to which it appertains to make and 10 use the same.

This invention relates to stands for displaying or showing articles of merchandise in store windows or other places in business houses of various kinds and classes, and the 15 object thereof is to provide an improved device of this class which is preferably made of cardboard, pasteboard, or similar fibrous material so that it will not injure glass or other polished shelves or supports when 20 placed thereon; a further object being to provide a display stand which is very light and composed of separate detachably connected parts, and may be conveniently set up for use or taken down for package or 25 shipment purposes, and the top of which is capable of adjustment into different positions.

The invention is fully disclosed in the following specification of which the accompanying drawing forms a part, in which the separate parts of my invention are designated by suitable reference characters in each of the views, and in which:—

Figure 1 is a side view of my improved 30 display stand with part of the construction broken away;—Fig. 2 a plan view of a blank from which the base or bottom of the stand is made;—Fig. 3 a similar view of a blank used in forming a part of the stem of the stand which is preferably composed of separate telescopic members;—Fig. 4 a central vertical section of the top portion of the 35 stand and showing a method of adjusting the table or top proper into different positions on the stem;—Fig. 5 a view similar to Fig. 4, but showing another adjustment of the top or table portion of the stand, and;—Fig. 6 a transverse section on the line 6—6 of Fig. 1.

In the practice of my invention, I provide 40 a display stand composed of a base or bottom *a*, a stem *b* and a table or top *c*, said parts being detachably connected and being formed as hereinafter described.

The base or bottom *a* is made in the form 45 of a truncated pyramid and is formed from

a blank *a*², shown in Fig. 2, and the top or table *c* is made in the form of an inverted truncated pyramid and is formed from a blank the same in form as the blank *a*² from which the bottom *a* is made, only the blank from which the top or table *c* is formed is of less dimensions than that from which the base or bottom *a* is formed. 60

The blank *a*² comprises a central rectangular body portion *a*³, the corner portions *a*⁴ of which are provided with folding neck portions *a*⁵ having folding truncated members *a*⁶, and the body *a*⁷ of the blank is provided with folding lines *a*⁸ forming an inner square, and a blank formed in this manner may be folded to form the base or bottom *a* of the stand and the top portion or table *c* thereof, it being understood that as the top portion or table *c* is made smaller than the base or bottom *a*, the blank from which said top portion or table is formed must be smaller than the blank from which the bottom or base portion *a* is formed. 65

When the bottom or base *a* and the top or table *c* are formed in the manner described, said parts are respectively provided with central vertical openings *d* and *e* which are rectangular or square in cross section and adapted to receive the end portions of the 70 stem *b*.

The stem *b* is composed of outer and inner tubular telescopic members *b*² and *b*³, said parts being rectangular or square in cross section and the inner tubular member *b*³ of 75 the stem *b* is preferably longer than the outer tubular member, and the outer tubular member is made from a blank *b*⁴, shown in Fig. 3, said blank being oblong or rectangular in form and one end portion thereof 80 being cut away at its opposite corners to form a triangular notch or recess *b*⁵ and the other or corresponding corner being cut away to form an oblong rectangular recess *b*⁶, and in practice this blank is folded to 85 form the outer tubular member *b*² of the stem *b*, and the notches or recesses *b*⁵ and *b*⁶ form in the top of said member, at one side thereof, a transverse recess *b*⁷.

The inner tubular member *b*³ of the stem 90 *b* is made from a blank somewhat smaller than that shown in Fig. 3, but longer and without recesses of any kind at the corners or ends thereof, and the inner member *b*³ is also preferably provided with transverse 95 partitions *b*⁸ which are designed to give strength thereto. 100

When the blanks from which the base or bottom *a* and top or table *c* are formed have been folded to form said parts, the separate portions of said blanks are firmly secured 5 together by paste, glue, or otherwise in the manner of making cardboard, pasteboard or other boxes of this class, and the separate parts of the stem *b* are also formed and secured in the same manner, and the base or 10 bottom member *a*, and the top or table *c* may be and are preferably covered with paper having a grained finish, or the parts *a*, *b*, and *c*, or the side portions thereof, may be colored or finished in any desired manner, 15 and the corners of the parts *a* and *c* are reinforced and secured by strips *f* in the same manner as the corners of cardboard or pasteboard boxes.

In practice the inner part *b*³ of the stem *b* 20 is made so as to be inserted into the opening *d* in the base *a* and closely fit the same, while the outer member *b*² of the stem rests on said base. The opening *e* in the top or table *c* is designed to receive the upper end of the 25 outer member *b*² of the stem which closely fits therein, and when the parts of the stem are in position, as shown in Figs. 1 and 4, the inner member *b*³ comes just to the bottom of the recess *b*¹ in the top of the outer 30 member *b*² and the table *c* may rest horizontally on the top of the stem or may be adjusted into the position shown in dotted lines in Fig. 4, or may be adjusted at an angle to the stem, as shown in full lines, the 35 notch or recess *b*¹ receiving one side edge of the wall of the opening *e* in the top or table; or the inner part *b*³ of the telescopic stem may be adjusted into the position shown in Fig. 5, when the table *c* may be supported at 40 a greater angle of inclination, as shown in Fig. 5.

It will be understood, of course, that the stand may serve as a means for displaying or showing articles of various kinds or 45 classes in stores and similar places, and may be used in display windows having glass shelves or on counters having glass tops, or on other polished surfaces, without injuring the same, and while I have described the 50 preferred form and method of making my improved display stand, it will be apparent that other changes therein and modifications thereof may be made, within the scope of the appended claims, without departing from 55 the spirit of my invention or sacrificing its advantages.

Having fully described my invention what I claim as new and desire to secure by Letters Patent is;—

60 1. A display stand comprising a base, stem and table, said base being of the form of a truncated pyramid, and the table being of the form of an inverted truncated pyra-

mid, said base and table being formed from 65 blanks of the same shape, and being provided with central openings to receive the opposite ends of the stem, and the stem being composed of separate telescopic members formed from blanks, the opening in the base member being adapted to receive one 70 end of the inner stem member, and the opening in the table being adapted to receive the opposite end of the outer stem member.

2. A display stand comprising a base, stem and table, said base being of the form 75 of a truncated pyramid, and the table being of the form of an inverted truncated pyramid, said base and table being formed from blanks of the same shape, and being provided with central openings to receive the 80 opposite ends of the stem, and the stem being composed of separate telescopic members formed from blanks, the opening in the base member being adapted to receive one end of the inner stem member, and the opening in the table being adapted to receive the 85 opposite end of the outer stem member, and the top of the stem being provided with means whereby the table may be supported in different positions thereon. 90

3. A display stand comprising a base, stem and table, said base being of the form of a truncated pyramid, and the table being of the form of an inverted truncated pyramid, said base and table being formed from 95 blanks of the same shape, and being provided with central openings to receive the opposite ends of the stem, and the stem being composed of separate telescopic members formed from blanks, the opening in the base member being adapted to receive one 100 end of the inner stem member; and the opening in the table being adapted to receive the opposite end of the outer stem member, said base, stem and table being all rectangular in 105 form in horizontal section.

4. A display stand composed of a base, a stem and a table, the stem being composed of separate telescopic parts one of which is longer than the other, and the base and table 110 being provided with central openings into which the separate parts of the stem are inserted, the opening in the base being adapted to receive the lower end of the inner part of the stem and the opening in the table to 115 receive the upper end of the outer part of the stem, said outer part of the stem being adapted to rest on the base.

In testimony that I claim the foregoing as my invention I have signed my name in 120 presence of the subscribing witnesses this 26th day of December, 1912.

ARTHUR BRACKLEY.
